ALBERT V. T. DAY, OF NEW ROCHELLE, NEW YORK, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

1,393,011.

Specification of Letters Patent. Patented Oct. 11, 1921.

Continuation of renewal application Serial No. 193,394, filed September 26, 1917, and a division of application Serial No. 637,773, filed July 10, 1911. This application filed April 4, 1918, Serial No. 228,584. Renewed August 18, 1921. Serial No. 493,432.

To all whom it may concern:

Be it known that I, ALBERT V. T. DAY, a citizen of the United States, residing at New Rochelle, in the county of Westchester 5 and State of New York, have invented certain new and useful Improvements in Railway - Traffic - Controlling Apparatus, of which the following is a specification.

My invention relates to railway traffic 10 controlling apparatus.

The present application is a division of my co-pending application filed July 10, 1911, Serial No. 637,773, for traffic controlling system, and is a continuation of my co-pending renewal application filed September 26, 1917, Serial No. 193,394, for railway traffic controlling apparatus.

I will describe one form of traffic controlling apparatus embodying my invention, 20 and will then point out the novel features thereof in claims.

The accompanying drawing is a view, partly diagrammatic, showing one form of traffic controlling apparatus embodying my 25 invention.

Referring to the drawing, R designates a track rail of a railway track, over which traffic moves in the direction indicated by the arrow. This traffic is controlled by signals located at intervals along the track, 30 two of which A and B, are shown in the drawing, each comprising a home semaphore H and a distant semaphore D. These signals are controlled by any suitable means, 35 which means are not shown in the drawing since they form no part of my invention. The block between signals A and B is occupied by a train T, hence signal A indicates stop; signal B indicates clear, showing that 40 the two blocks in advance of block A—B are unoccupied.

The train T carries apparatus which is operated by the movement of the train and which tends, after movement of the train 45 through a predetermined interval of space, to accomplish some suitable function operating to stop the train or to give a signal to the driver thereof. As here shown, this apparatus opens a valve connected with the 50 train pipe, thereby causing an application of the brakes. The escape of air from a pipe 57, which leads to the train pipe, is controlled by a piston valve comprising a

valve cylinder 55 communicating with pipe 57 and having an opening 56 in the side 55 thereof which is opened and closed by the movement of a piston 54 in the cylinder. The piston 54 is provided with a long downwardly extending piston rod 51 which is adapted to be engaged by a mechanical resetting means hereinafter explained and pushed up thereby. The piston and rod tend to fall by gravity, but are restrained by means connected with a wheel or axle of the train so that the downward movement of 60 the piston is in accordance with the movement of the train along the track.

As here shown, the restraining means comprises a shaft 14 on which is fixed a worm wheel 13 which meshes with a worm 70 12 on an axle 30 of the vehicle, so that as the vehicle proceeds in the direction indicated by the arrow on the wheel, shaft 14 is rotated in the direction indicated by the arrow around this shaft. A worm 15 on the 75 shaft 14 meshes with a worm wheel 16 fixed on a shaft 17 which latter is suitably mounted on the vehicle. Loosely mounted on the shaft 17 is a pinion 48 which coacts with a detent 18, which latter is pivotally mounted 80 on the worm wheel 16 and is pressed into the teeth of the pinion 48 by a spring 130 with sufficient force to cause the pinion to be rotated when the worm wheel is rotated; the spring will, however, yield to permit the 85 pinion to be rotated independently of the worm wheel 16.

The piston rod 51 is provided with a rack 49 with which the pinion 48 meshes. As the train moves in the direction indicated by 90 the arrow in the trackway, the worm wheel 16 is rotated in the direction indicated by the arrow thereon, and the pinion 48 is rotated in the same direction due to the engagement of the detent 18 with the teeth of 95 the pinion, so that the piston 54 and rod 51 are permitted to fall gradually in accordance with the progress of the train.

The parts thus far described are so designed that if the piston 54 is raised at the 100 entrance end of a block, as for example, at signal A, the train will run one block and a slight distance into the next block, to a point *x* for example, at which point the pinion 48 will have rotated sufficiently to 105 permit the piston 54 to open the vent 56,

thereby causing an application of the brakes, unless the piston has in the meantime been raised again.

Located at intervals in the trackway are devices adapted to reset the train-retarding apparatus; that is, to raise the piston 54. As here shown, such a device is located adjacent each signal A and B, and is controlled by the distant semaphore of the adjacent signal. Each device comprises two toggle links 68 and 71, located in the path of movement of a wheel 52 journaled on the end of the piston rod 51. The link 71 is pivoted to the track rail by a pin 72 and a corresponding pin 70 passes through a slot 69 in the end of link 68, thus permitting the toggle to be raised and lowered. The toggle is controlled by the distant semaphore D of the adjacent signal through the following mechanism: Operatively connected with the semaphore is a vertical rod 61 which is connected with one arm of a bell crank lever 62 the other arm of which is connected with a rod 65 beside the track. The other end of rod 65 is connected with one arm 66 of a bell crank lever pivoted at 64, the other arm 66^a of which is connected with a link 67. This link is also connected to the pivot 67^a joining the toggle links 68 and 71. When the semaphore D is in the inclined position (as shown at signal B) it raises the toggle links through the mechanical connections just described, so that these links are in position to reset the apparatus on the train. When, however, the semaphore D is in the horizontal position (as shown at signal A), the toggle links 68—71 are depressed so that they are out of the path of the wheel 52 on the train retarding apparatus.

When a train approaches a signal station, the piston 54 and wheel 52 have fallen to nearly the lowest position of their stroke. This is the condition of the parts on train T, which has nearly reached signal B. The two blocks in advance of block A—B are unoccupied, hence signal B indicates "clear"; the adjacent toggle 68—71 is therefore elevated so that wheel 52 will be raised by link 71 thereby raising rod 51 and piston 54 and thus resetting the apparatus so that the train may proceed unretarded to the next signal. While the train retarding apparatus is being thus reset, spring 130 yields and thus permits the pinion 48 to rotate idly on shaft 17. If, however, one or the other of the two blocks in advance of block A—B were occupied by a car or train, signal B would indicate "caution" or "danger" and the adjacent toggle would be depressed so that wheel 52 would not be raised; the train would then be brought to a stop at point x a short distance in advance of signal B.

Below the rack 49 is a recess 50, the pur-

pose of which is as follows: When the train is run backward, the pinion 48 will elevate the piston 54 until the pinion runs off from the rack 49 into the recess 50 after which the piston will not be raised farther but the pinion 48 will rotate idly in the recess 50 and no damage will be caused.

To enable the driver to run the train slowly after passing a caution signal while at the same time compelling him to be at his post where he can keep the train under control, a manual hold-out is provided for partially resetting the apparatus to permit the train to proceed a short distance. This hold-out comprises a pin 53 on the rod 51 which engages a hold-out arm 58 substantially at the time that the brakes are applied. The arm 58 may be oscillated between two fixed pins 60 and 59 thus partially resetting the apparatus and permitting the train to run a short distance before the brakes will be applied.

In order that the driver of the train may always know the position of the piston 54 and so be enabled to ascertain how far he may proceed before the brakes will be applied, a pointer or index 63 is attached to the piston rod and arranged to coöperate with a stationary pointer 63^a, the two pointers being so arranged that they will be in alignment just as the piston 54 opens the vent 56.

I do not claim in this application the broad subject matter disclosed herein, such claims being in my patent application Serial No. 637,773, of which the present application is a division.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a railway track, a vehicle adapted to travel thereon, apparatus on the vehicle connected with a wheel or axle thereof and capable of an operative position which it approaches in accordance with the movement of the vehicle, vehicle-governing means rendered operative by said apparatus when the latter reaches said operative position, and devices located at intervals in the trackway for mechanically resetting said apparatus away from said operative position.

2. In combination, a railway track, a vehicle adapted to travel thereon, apparatus on the vehicle connected with a wheel or axle thereof and capable of an operative position which it approaches in accordance with the movement of the vehicle, vehicle-governing means rendered operative by said

- apparatus when the latter reaches said operative position, a member on the vehicle for resetting said apparatus away from operative position, devices located at intervals in 40
5 the trackway and adapted to engage said member for operation thereof, each device being movable into and out of the path of said member, and means for each device for the control thereof.
- 10 3. In combination, a railway track, a vehicle adapted to travel thereon, apparatus on the vehicle connected with a wheel or axle thereof and capable of an operative position which it approaches in accordance with the 45
15 movement of the vehicle, vehicle-governing means rendered operative by said apparatus when the latter reaches said operative position, inclined members located at intervals along the trackway, a roller on the vehicle 50
20 adapted to be moved by said inclined members and to thereby reset said apparatus away from operative position, and means for moving each inclined member into and out of the path of said roller.
- 25 4. In combination, a railway track, a vehicle adapted to travel thereon, apparatus on the vehicle connected with a wheel or axle thereof and capable of an operative position which it approaches in accordance with the 55
30 movement of the vehicle, vehicle-governing means rendered operative by said apparatus when the latter reaches said operative position, a member on the vehicle for resetting 60
35 said apparatus away from operative position, signals located at intervals along the trackway, and devices operatively connected with said signals and movable thereby into and out of the path of said member, each 65
70

device being adapted when in the path of said member to move the latter to cause the apparatus to be reset away from operative position.

5. Railway traffic controlling apparatus comprising means on a vehicle arranged to change gradually toward an ultimate condition, traffic governing apparatus on the vehicle controlled by said means, and devices located in the trackway for mechanically resetting said means away from ultimate condition. 50

6. Railway traffic controlling apparatus comprising means on a vehicle arranged to change gradually toward an ultimate condition, within a given distance traveled by the vehicle, traffic governing apparatus on the 55 vehicle controlled by said means, and devices located in the trackway and responsive to clear traffic conditions in advance for mechanically resetting said means away from ultimate condition before such condition is 60 reached.

7. Railway traffic controlling apparatus comprising a member carried on a vehicle and arranged to move downwardly from an initial position to an ultimate condition 65
within a given interval, brake applying apparatus controlled by said member, and devices located in the trackway for mechanically raising said member to its initial position. 70

In testimony whereof I affix my signature in presence of two witnesses.

ALBERT V. T. DAY.
